UNITED STATES PATENT OFFICE.

GUSTAV KARL HENNIG, OF BÖHLITZ EHRENBURG, NEAR LEIPZIG, GERMANY, ASSIGNOR
TO THE FIRM OF LUDWIG HUPFELD, A.-G. BÖHLITZ, EHRENBURG NEAR LEIPZIG,
GERMANY.

PLURAL-NOTE-SHEET MECHANISM.

1,216,448.

Specification of Letters Patent.

Patented Feb. 20, 1917.

Application filed September 24, 1913. Serial No. 791,543.

To all whom it may concern:

Be it known that I, GUSTAV KARL HENNIG, a subject of the King of Saxony, residing at 1 Bielastrasse, Böhlitz Ehrenberg, 5 near Leipzig, Germany, have invented certain new and useful Improvements in Plural-Note-Sheet Mechanism; and I do hereby declare the following to be a full, clear, and exact description of the invention.

10 My invention relates to playing mechanism for pneumatically actuated musical instruments in connection with a plurality of note sheets, and may be termed broadly "plural note sheet mechanism."

15 The broad idea of using a plurality of note sheets is well known.

My invention has for its object to effect the movements of the plural note sheets either independently or simultaneously.

20 The control of the note sheets whereby they are caused to travel either simultaneously or separately, is accomplished either by the note sheets themselves or by the person playing the instrument.

25 The note sheets may control the playing of the same sounding apparatus or of different sounding apparatus, so that, for example, a solo and an accompanying instrument may be played, as a piano and a violin, flute, 30 or the like.

The note sheets may also act to mutually synchronize one another.

In the accompanying drawings the essential features embodying my invention are 35 shown in one type of apparatus, and in said drawings—

Figure 1 is an elevation, partly in section, of the apparatus in connection with the tracker bars and the note sheet motors.

40 Fig. 2 shows portions of each note sheet of a pair perforated for synchronizing.

Fig. 3 shows other portions of the same pair of note sheets for solo and accompaniment playing.

45 Fig. 4, illustrates the mechanism in connection with electrically driven note sheet rolls.

The instrument illustrated in Fig. 1 as a type, is constructed for the simultaneous 50 use of two note sheets. However, any number of note sheets may be coördinately used, it being simply necessary to increase the number of related parts, as the tracker bars, note sheet motors, and the like.

55 In the instrument shown there are two

note sheet chests, *a* and *b*, having respectively, tracker bars *c* and *d*, and motors *e* and *f*, which may be the usual wind motors, for operating the note sheet rolls in a well known manner.

60 By the aid of controlling pneumatics and controlling valves, a simultaneous synchronized movement of the two note sheets may be accomplished, or the movement of either note sheet, at will.

65 In order to attain the synchronous or asynchronous travel of the note sheets this may be automatically controlled by the note sheets themselves, which are provided at a suitable point with control perforations, for example, at the side of the sheet, at the middle of the sheet, or at any other position transversely of the sheet that may be chosen, the perforations extending longitudinally of the several sheets, and the perforations in 70 the row of each sheet being the same distance apart, except for purposes hereinafter specified.

75 If one of the note sheets is to remain stationary and the other to continue the play- 80 ing, then the control perforations of the sheet that is to continue its movement are not continuous, and are omitted for the distance required to perform the individual or solo part of the music.

85 The tracker bars for the several note sheets each have a special opening over which the control perforations of the sheet pass. These openings are shown at *E* and *F* on the drawings.

90 The openings *E* and *F* are respectively connected by conduits or tubes *g* and *h* which tubes are connected to valves *l*, *m*, and *i*, *k*, respectively. The valve members *m* and *k* control the control passages *o'* and 95 *n* to the members *q*, *p*, of a double pneumatic *P*.

99 The member *q'* connecting the movable members *p*, *q* of the double pneumatic *P* is provided with a pin or lug *q''* arranged to 100 travel between spring-urged valves *r* and *s* that control the admission of outside air to the conduits *t* and *u*, both connected to a valve chest *W*, having two double valves *v*, *w*, and *x*, *y*. The conduit *t* terminates at 105 a membrane *v'* for controlling the double valve *v*, *w*, and the conduit *u* terminates in a membrane *x'* for controlling the double valve *x*, *y*.

The double valve *v*, *w* controls a conduit 110

that leads to a membrane 2' of a valve 2, while the double valve x y controls a conduit 3 to a membrane 4' of a valve 4. Valves 2 and 4 control the conduits 5 and 6, leading respectively to pneumatics 7 and 8. The pneumatics 7 and 8 operate double valves 9 and 10, which in turn control the conduits 11 and 12 leading to the motors e and f for the note sheet rolls.

10 The apparatus operates as follows, in connection with note sheets A and B having their control perforations C D arranged at equal intervals, as shown in Fig. 2, the note sheets traveling in the direction of the arrow.

15 15 The control perforations C are for convenience arranged at the sides of the sheets and coöperate with the tracker-bar openings E and F respectively. As long as the note sheets A and B travel in synchronism their control perforations C and D simultaneously 20 pass over their respective tracker-bar openings E and F, so that the pressures existing in the two sides of the double pneumatic P remain equal and it is maintained in its middle position. In other words the pin q^2 25 does not operate the valves r and s by reason of the simultaneous inflation of membrane i and l , resulting in the simultaneous lifting of valves k and m to place the members p q of the double pneumatic P through 30 their passages n o under the same suction, namely the suction existing in chambers i' and l' . As soon as a control perforation C or D of one of the note sheets A or B registers with its tracker bar opening E or F 35 slightly ahead of the other, the double pneumatic P is at once actuated.

If for example, as shown in Fig. 2, the 40 perforation C registers with the opening E slightly in advance of the registration of the corresponding perforation D of sheet B with its tracker bar opening F, outside air is admitted through tube g to lift valve m and place the member q of the double pneumatic P under suction, and thereby move the rod q' so that its pin q^2 will open the spring- 45 closed valve r , Fig. 1. Outside air is thus admitted to conduit t and membrane v' to lift the double valve v w to admit outside 50 air to conduit 1 to inflate the membrane 2' and lift valve 2, cutting off the outside air from conduit 5 and placing said conduit and its connected pneumatic 7 under suction. The collapse of pneumatic 7 raises double 55 valve 9, so that outside air will be admitted to conduit 11 to the wind motor e , which, no longer being under suction momentarily stops the motor and the note sheet A driven thereby. This action lasts only an instant 60 that is to say, only until the corresponding control perforation D of the other note sheet B has been moved to its tracker bar opening F, whereupon outside air is admitted to conduit h to inflate membrane i , raise valve k 65 and place p also under suction, whereupon

pneumatic P again assumes its normal or middle position, valve r is closed, and both note sheets again travel simultaneously until one or the other of the note sheets advances, whereupon the synchronizing again takes place.

From what has previously been described the travels of the note sheets have been synchronized, but the mechanism is not limited in its action to synchronizing only, but 75 will permit, with suitable arrangement of the control perforations C. D. any desired extent of travel of either note sheet while the other remains stationary. Note sheets perforated for this purpose are illustrated 80 in Fig. 3.

The note sheet A' has control perforations C like the note sheet A, Fig. 2, arranged in regular succession, but the note sheet B' has the control perforations D omitted for a 85 considerable distance, indicated at G. The omission of the perforations D for the distance G in sheet B' causes the note sheet A' to remain stationary until the note sheet B' has traversed the distance G and the following perforation D registers with the tracker bar opening F.

Exactly the same mechanism is used as described in connection with Fig. 2, as the wind motor e is vented to the atmosphere 95 and stops until the following perforation D in sheet B' again causes the double pneumatic P' to assume middle position, whereupon both motors are placed under suction. In this manner one or the other set of sounding mechanisms may be temporarily rendered inoperative.

For example, if one of the note sheets controls the playing of a violin, and the other the playing of a piano to accompany 105 the violin, then during a pause or rest in the violin playing, the violin controlling note sheet will remain stationary, and vice versa, the piano controlling note sheet may remain stationary during a pause or rest in the 110 piano music.

Heretofore it has been necessary that both note sheets should travel, both during the pause and during the playing, so that, for example, in a violin solo, accompanied by a 115 piano, the violin controlling note sheet, where not perforated for playing the violin, would be simply blank paper for a greater or less distance that passed over the tracker-bar requiring power to be supplied to the 120 wind motor for causing the travel of the sheet, and an unnecessary use of paper, causing the sheet to be unnecessarily long.

This invention renders it possible to use 125 note sheets only of such length as is actually required for producing the tones, as the sheet remains stationary where there are pauses or rests, and thereby considerable motive power is saved.

Several instruments, with their note sheets 130

and motors can be suitably actuated in this manner as well as synchronized.

The control may be manual only, if desired, or both manual and automatic. For 5 manual operation the double pneumatic P may be moved by hand, so that the player can thus operate either valve, *r* or *s*, to cause the corresponding note sheet to remain stationary.

10 To this end I have shown the rod *g'* connected by a link 20 to a lever 21 mounted at any point within convenient reach of the operator. It is, of course, obvious that instead of using a single lever and connections 15 with the double pneumatics, any other lever arrangement may be used for venting the motors to the atmosphere and cutting off their suction connection.

15 and 16 are clutches in the driving connection between the motors *e* and *f* and the driven note sheet rolls. The clutch 16 is operated by pneumatic 14 connected by conduit 17 to conduit 5. The clutch 15 is operated by pneumatic 13, connected by conduit 25 18 to conduit 6, so that the clutches may be simultaneously actuated when their motors are vented to the atmosphere. In case the note sheet rolls are driven by electric motors (Fig. 4), then all the pneumatic mechanism 30 beyond the conduits 5 and 6 may be omitted and the conduits 17 and 18 for operating the clutches are substituted for the conduits 5 and 6. The electric motors *M* are not stopped, but simply uncoupled.

35 I claim as my invention:

1. In a pneumatically operated musical instrument, the combination with a pair of music sheets having synchronizing perforations, and unperforated solo control portions; of mechanism for actuating the music sheets under the control of both sheets whereby the unperforated portion of one sheet while playing its solo part will cause the other sheet to remain stationary.

45 2. In a pneumatically operated musical instrument the combination with a plurality of note sheets having perforate and imperforate control portions arranged in longitudinal rows, said perforated portions having regularly spaced perforations and the imperforate portions varying in length, of pneumatic sheet tracking mechanisms for said note sheets, and a pneumatic mechanism under the control of said perforations 50 and controlling said tracking mechanism.

3. In a pneumatically operated musical

instrument the combination with a plurality of note sheets, said note sheets each having a single row of side hole control perforations regularly spaced, and one or more of 60 said sheets having imperforate portions in said row in accordance with the length of the solo part of said sheet, of a pneumatic device under the control of the perforations in all of the sheets, and a tracking mechanism 65 for each sheet controlled by said device.

4. In a pneumatically operated musical instrument, trackers, a registration means in each tracker, a plurality of note sheets having perforated and unperforated portions in 70 position to pass over said means, said perforated portions having regularly spaced perforations, a double pneumatic controlled by the perforations in said note sheets maintained inoperative when the latter travel 75 synchronously and operated when said sheets do not travel synchronously, a pneumatic mechanism for operating each note sheet, and a single actuating member controlled by the double pneumatic for controlling the opera- 80 tion of said operating mechanism.

5. In a pneumatically operated musical instrument, trackers, a registration means in each tracker, a plurality of note sheets having perforated and unperforated portions 85 in position to pass over said means, said perforated portions having regularly spaced perforations, a double pneumatic controlled by the perforations in said note sheets maintained inoperative when the latter travel 90 synchronously and operated when said sheets do not travel synchronously, a pneumatic mechanism for operating each note sheet, a valve for controlling the operation of each pneumatic mechanism, and a single valve- 95 actuating member carried by the double pneumatic.

6. In a pneumatically operated musical instrument using a plurality of note sheets and pneumatic motor mechanism; pneumatic mechanism controlled by perforations in said sheets to independently and simultaneously vent said motors to the atmosphere at will.

In testimony whereof I have signed my 105 name to this specification, in the presence of two subscribing witnesses.

GUSTAV KARL HENNIG.
